UNITED STATES PATENT OFFICE.

JOSEPH HENRY BACON, EBENEZER S. BACON, AND VAN CORTLAND SECORD,
OF DETROIT, MICHIGAN.

AUTOMATIC WASTE-VALVE.

SPECIFICATION forming part of Letters Patent No. 330,664, dated November 17, 1885.

Application filed September 10, 1885. Serial No. 176,676. (No model.)

To all whom it may concern:

Be it known that we, JOSEPH H. BACON, EBENEZER S. BACON, and VAN CORTLAND SECORD, of Detroit, in the county of Wayne and State of Michigan, have invented new and useful Improvements in Automatic Waste-Valves; and we do hereby declare that the following is a full, clear, and exact description thereof, reference being had to the accompanying drawings, which form a part of this specification.

This invention relates to certain new and useful improvements in means for keeping up a circulation of water in and through service-pipes, to prevent the water in the latter from freezing.

The fact that many accidents occur and much trouble is occasioned by the freezing up of the contents of the water service-pipes, especially in rigorous climates, is too well known to need explanation. It is also well known that large quantities of water are wasted during the winter season by house-keepers leaving their water-faucets open in order to keep the flow under the ordinary pressures, thereby preventing disaster. It is also well known that a very small discharge will so keep the current passing through the pipes as to prevent freezing up.

The object of the present invention is to provide a valve to control a waste-opening, such valve being actuated by the temperature in such a manner that at or near the freezing-point it will automatically open a discharge to the waste, thereby producing a circulation of water in the service-pipe with a minimum loss of water.

Figure 1 is an elevation showing one method of applying our device to the ordinary house service-pipe in the kitchen. Fig. 2 is a vertical central section through the valve and its connections.

In the accompanying drawings, A represents the water service-pipe connected with the street main and leading into the sink B of the kitchen. C is the waste-pipe leading from such sink to the sewer or other suitable place of discharge, and these are of the well-known construction and application. D is a tube, made of any suitable material, connected by means

of a branch pipe, C', near its top, with the service supply-pipe A, and a valve, a, may be inserted in this connecting-pipe C', which may be beneficially used to cut off communication between A and D in moderate weather, when there is no danger of freezing, although this is not essential to the perfect working of our device. The lower end of the tube communicates by means of a branch or pipe, b, with the waste-pipe C. At the lower end of the tube D, and in a suitable chamber for the purpose, there is fitted the valve-seat c, upon which the valve E seats itself to cut off the flow of water to the waste-pipe. The stem F of this valve E is so connected by any of the known means with the valve as to allow the latter to slightly oscillate, the more readily to seat itself under all contingencies, and this rod or stem is made of any metal, like zinc or brass, the expansion and contraction of which under varying temperatures is much greater than that of iron, lead, or other suitable material from which the tube D is made. Screwed upon the top of the tube D is a hollow cap, G, through which the rod H passes, such rod having at each end a thread cut thereon, that upon the lower end screwing into the top of the stem F, while that at the upper end is provided with an adjusting-nut, d, and a jam-nut, e, and these parts are so arranged and adjusted that at the ordinary temperature of the water the valve is kept to its seat by the pressure of the water, but as soon as the temperature falls to or near the freezing-point the contraction of the stem will raise the valve from its seat and allow the water from the service-pipe to pass through the tube D to the waste, and thus produce a circulation which prevents the freezing of the water, and as the coldness of the water increases the contraction of the stem becomes greater, thereby allowing a greater flow of water through to the waste, but on the temperature becoming normal again the expansion of the stem will gradually close said overflow through the valve.

We do not desire to confine ourselves to the position of the relative parts as shown in Fig. 1, nor to the construction of the parts as shown in Fig. 2, for we know that various

modifications of this arrangement and construction may be had which we consider would come within the spirit and scope of our invention.

- 5 As our device is only wanted to operate during the cold season of the year, we provide the pipe C' with a valve, a', by means of which communication may be cut off between the service-pipe and the tube D.
- 10 We are aware that it has been proposed to accomplish the same result by means of a waste-valve and a rod of metal subject to changes, operated by mechanism arranged outside the building. This has been found
- 15 objectionable, for the reason that the valve is often opened when it is not necessary that it should be. By our construction the valve is not opened till the temperature of the room and of the water in the conduit is nearly at a
- 20 freezing-point.

What we claim as our invention is—

1. In combination with a water service-pipe and a waste-water pipe, a conduit connected with both, and a valve arranged within 25 said conduit and provided with a rod for operating the same, the expansion and contraction of which differs from that of the said conduit, said valve being actuated by the changes of temperature of the water in said 30 conduit, as set forth.
2. In combination with a water service-pipe and a waste-water pipe, a conduit connected with both, and a valve arranged within said conduit and provided with a stem or rod of 35 metal the expansion and contraction of which is greater than that of the said conduit, said rod being actuated by the changes of temperature of the water in said conduit, as set forth.

3. In combination, the service-pipe A, communicating with any suitable water-supply, 40 the conduit D, having a connection with such service-pipe, a valve, E, seated in such conduit D and controlling the outflow through the connection with the waste-pipe, and provided with a valve stem, F, of metal the expansion 45 and contraction of which is greater than that of said conduit, substantially as and for the purpose specified.

4. In combination with a water service and a waste-water pipe, a conduit connecting near 50 its upper end with the former and at its lower with the latter, and having a valve seated therein to control the passage of water to such waste-pipe, such valve having within said conduit a stem adjustably secured at its upper 55 end and made of metal the expansion and contraction of which is greater than that of the said conduit, substantially as set forth.

5. In combination, the service-pipe A, communicating with any suitable water-supply, 60 the conduit D, having a connection, C', with such service-pipe, a valve, E, seated in such conduit D, and controlling the outflow through the connection b with the waste-pipe C, a valve-stem, F, actuating such valve E, a cap, 65 G, on the top of such conduit, a rod, H, tapped into the top of such valve-stem, and adjusting-nut d upon such rod H, the parts being constructed and operating substantially as and for the purposes described.
